Attorney

UNITED STATES PATENT OFFICE.

GEORGE H. HILBERS, OF HOOPER, NEBRASKA.

LOCKING DEVICE FOR CRANKS.

1,238,912.

Specification of Letters Patent.

Patented Sept. 4, 1917.

Application filed December 7, 1916. Serial No. 135,620.

To all whom it may concern:

Be it known that I, GEORGE H. HILBERS, a citizen of the United States, residing at Hooper, in the county of Dodge and State 5 of Nebraska, have invented certain new and useful Improvements in Locking Devices for Cranks, of which the following is a specification.

The present invention relates to improvements in locking devices for cranks.

The primary object of the invention is the provision of means whereby a crank can be locked in any of its adjusted positions and held therein against undesired movement.

15 A further object of the invention is the provision of means carried by a crank and engaging a suitable support for the purpose of locking the shaft to which the crank is applied against any undesired rotation.

20 A further object of the invention is the provision of a device of the nature above referred to, which will be comparatively simple and inexpensive to manufacture, reliable and efficient in use, and readily operated.

25 With the above and other objects in view the present invention resides in the novel features of construction, formations, combinations and arrangements of parts to be hereinafter more fully described, claimed, and illustrated in the accompanying drawing forming a part of the present application and in which:

Figure 1 is a side elevation of the invention;

Fig. 2 is a top plan view thereof; and

Fig. 3 is a transverse sectional view taken on the line 3-3 of Fig. 2.

Referring to the accompanying drawing 40 by corresponding characters of reference throughout the several views, the numeral 5 designates in general a portion of a frame or support in which is journaled a shaft 6.

This shaft 6 is mounted in a suitable 45 bearing 7 provided with an enlarged body portion 8 forming a crown gear including a plurality of teeth 9 and an attaching flange 10 which is bolted or otherwise secured in any preferred manner such as shown at 11 to the said frame 5.

A hand wheel 12 is keyed to the upper end of the shaft 6 and has secured thereto in any suitable manner a hollow wrist pin 13.

The upper end of the wrist pin 13 is enlarged as at 14 and fits within a recess 15

formed in the upper portion of a hollow rotatable handle 16 which is mounted upon the said wrist pin 13 being held thereon by the before described head.

An operating rod 17 is longitudinally 60 movable through the hollow wrist pin 13 and is provided at its upper end with a head 18 spaced normally a slight distance above the upper ends of the members 13 and 16.

The forked end 19 of a releasing grip 20 65 is disposed between the ends of the members 13 and 16 and the under side of the head 18 while the handle thereof extends downwardly at a slight angle relative to the handle 16. This releasing grip 20 is pivoted 70 as at 21 between ears 22 formed upon the side of the handle 16 adjacent the upper end thereof.

Obviously as the handle 16 is grasped by the operator the releasing grip 20 will be 75 engaged by the fingers of said operator and forced inwardly in the direction of the arrow shown in Figs. 1 and 3. This will obviously rock the forked end 19 upwardly causing the upward movement of the rod 17 80 and connecting link 23 which is pivoted as at 24 to the lower end thereof.

The lower end of the link 23 is pivoted to a sliding locking pawl 25 mounted in spaced parallel bearings 26 provided at one side of 85 a casting 27. This casting 27 is provided with a tubular portion 28 which receives the said shaft 6 being held thereon against any undesired movement by a key or the like such as shown at 29.

The lower end of the pawl 25 is provided 90 with a sharpened terminal 30 adapted to engage between the teeth 9 of the crown gear 8 in which position it is forced by the spring 31. Obviously when the releasing grip 20 is 95 disengaged by the fingers of the operator the spring 31 will force the locking terminal 30 of the pawl 25 between the before mentioned teeth 9 which holds the shaft 6 against rotation.

As the operator grasps the handle 16 and releasing grip 20 the latter is moved inwardly which causes the upward movement of the rod 17, link 23 and pawl 25, disengaging the locking terminal from between the 105 teeth 9. When in this position the shaft 6 can be rotated as desired and when the same has been turned to its proper position the release of the member 20 causes the spring 31 to force the pawl 25 again into engage- 110

ment with the teeth of the crown gear 8 thereby locking the shaft 6 in such position against any undesired displacement.

From the foregoing description taken in connection with the accompanying drawing it will be manifest that a locking device for cranks is provided which will fulfil all of the necessary requirements of such a device, and it should be understood in this connection that various minor changes in the specific details of construction can be resorted to within the scope of the appended claims, without departing from the spirit or sacrificing any of the advantages of the invention, and while the illustrations accompanying the present application show the device used in connection with a steering shaft and crank for tractors, it should be understood that I am not to be limited to such use alone but may connect the same to any other device to which the various parts thereof will adapt themselves.

Having thus described the invention what is claimed is;

1. The combination in a device such as described, with a shaft, and a crank secured thereto embodying a hollow wrist pin, a rod longitudinally movable within the wrist pin, a rotatable handle carried by the wrist pin, a releasing grip pivoted to the wrist pin, a forked extension provided upon said releasing grip and engaging the rod for moving the same vertically within the hollow wrist

pin upon movement of the releasing grip, an operating means supported by the shaft 35 for locking the latter against rotation, and a link connection between the movable rod and locking means.

2. In a device such as described, the combination with a shaft, a hand wheel secured thereto and a wrist pin extending from the hand wheel, said wrist pin having an enlarged head, a handle rotatable upon the wrist pin and having a recess receiving said enlarged head whereby the handle will be supported upon the wrist pin, a rod slidable within said wrist pin and having a head spaced above the upper end of the wrist pin and handle, a releasing grip pivoted upon said handle, a forked extension formed upon the releasing grip and engaging the rod beneath the head thereof whereby upon inward movement of the releasing grip, the rod will be raised within the wrist pin, a crown gear disposed adjacent the shaft, a casting secured to the shaft adjacent the crown gear, a pawl slidable within the casting for engaging the teeth of the crown gear, a spring actuating the pawl, and a link connection between said pawl and operating rod. 60

In testimony whereof I affix my signature in the presence of two witnesses.

GEORGE H. HILBERS.
